UNITED STATES PATENT OFFICE.

WILLIAM S. MENDEN, OF BROOKLYN, NEW YORK.

STREET-RAILWAY AND OTHER CAR.

1,094,805.

Specification of Letters Patent. Patented Apr. 28, 1914.

Application filed December 2, 1913. Serial No. 804,226.

To all whom it may concern:

Be it known that I, WILLIAM S. MENDEN, a citizen of the United States, residing in the borough of Brooklyn, county of Kings, 5 and State of New York, have invented certain new and useful Improvements in Street-Railway and other Cars, of which the following is a full and clear specification.

10 This invention relates more especially to that type of passenger cars which embody means for temporarily providing reservations for the motorman or other operator on the platforms of said car, such reservations 15 being adapted at other times for the reception of seats or other purposes.

More particularly, the present invention 20 contemplates the provision of a collapsible partition of improved construction, combination and arrangement of parts for enabling the partition to be rapidly set up or collapsed.

Collateral objects of the invention will 25 appear in the specification and claims, reference being had to the accompanying drawings in which the invention is exemplified.

In the drawings, Figure 1 is a general 30 plan view of the forward end of a passenger car provided with my improvements; Fig. 2 is the same general plan view of the rear end of the same car; Fig. 3 is a side elevation of the forward end, parts being broken away and parts shown in section; Fig. 4 is a fragmentary vertical section of the curtain bulkhead, parts being shown in elevation; Fig. 5 is a fragmentary plan view of 35 one portion of the partition, parts being broken away and parts shown in section; Fig. 6 is a similar fragmentary plan view 40 of another portion of the partition, parts being broken away and parts shown in section; Fig. 7 is a detail.

Referring more particularly to the drawings, the embodiment shown therein is a 45 rapid transit car provided with a central aisle 1 which opens at the forward end of the car onto a forward platform 2 and at the rear end of the car onto a platform 3, the arrows in both figures indicating the direction 50 of movement of the car. It will be understood that the forward and rear platforms 2 and 3 embody the same parts disposed in different positions. Referring to Fig. 1, a controller box 4 is disposed at each 55 end of a car. The partition which consti-

tutes the primary objective of the present invention, comprises in the present embodiment, the partition sections 5 which are hinged at 6 on opposite sides of the controller box 4, said partition sections being 60 adapted thereby to be folded into position against the panels 7 of the end wall of the car, as shown in Fig. 2, or to be folded out into partition forming position as shown in Fig. 1. Adjacent to the inside lateral edge 65 of the left hand section 5 of the partition is secured a bracket 8 provided with spaced bearing lugs or cheeks 9 within which is mounted a pivot stud 10. Pivotaly mounted on the stud 10, is one end of a tie bar 11 70 which is adapted to hold the sections 5 of the partition in the positions shown in Fig. 1 by having its other end provided with a latch mechanism as shown in Fig. 6.

As shown in Figs. 5 and 6 the tie bar 11 75 comprises a hollow tube within one end of which is secured a plug 12 by means of a pin 13. The plug 12 serves to mount an annular plate 14 which is movably disposed between the lugs or cheeks 9 and pivoted 80 upon the pin 10, the pin 10 being retained in position by means of a pin 15. Within the other end of the tubular tie bar 11, is mounted a cylindrical shell 16 which is slotted at its outer end to receive a block or post 17 85 which projects upwardly from the bracket arm 18 secured to the right hand section 5 of the partition.

As shown in Fig. 7, the keeper block 17 is provided with a recess 19 within which the 90 bolt 20 shown in Fig. 6 is adapted to fit. The bolt 20 is reciprocably mounted within a bore 21 which extends inwardly from the slotted outer end of the shell 16. Within the bore 21 is mounted a spring 22 which 95 impinges at one end against the bottom wall of the bearing 21 and at its other end against the enlarged bolt head 20, said bolt 20 being provided with a stem 23 which projects through the end wall of the cylindrical shell 100 16, being held against displacement from the shell 16 when the tie bar is raised out of operative position, by a pin 24 which passes through the stem 23 on the inside face of the end wall of the shell 16. 105

As shown in Figs. 5 and 6, each of the partition sections 5 carries a vertical guide, preferably in the form of a channeled section 25. Integral with each of the channeled guides 25 is a base plate 26 by means 110

of which said guide is secured to the partition section 5. Said guides 25 are adapted to reciprocably mount the end of a curtain rod 27 which is suspended in any suitable manner from the lower end of a curtain or flexible panel 28. Preferably the curtain rod 27 is provided with resiliently mounted clamping rods 29. Referring now to Fig. 4, a bulkhead or housing for the curtain or flexible partition 28, is provided adjacent the upper ends of the partition sections 5 by means of a flat plate 30, which has a portion 31 displaced therefrom to form the forward wall of said housing or bulkhead, said portion 31 being bent around into the form shown in Fig. 4, and provided with a flat bent portion 32 which is secured to the main body of the plate 30. The rear wall 33 and end walls 34 complete the housing or bulkhead, said end walls 34 being provided with suitable means for journaling the ends 35 of a curtain roller 36, the several parts being suitably disposed so that when the curtain 28 is drawn downwardly at 25 a tangent to the rolled curtain 28 as shown in Fig. 4, the ends of the rod 29 are suitably positioned to enter the slotted guides 25. On each of the platforms 2 and 3, is provided suitable and efficient means for seating passengers when the partition comprising sections 5 and panel 28, is collapsed. For this purpose, each platform is provided with a pair of oppositely disposed fixed seat sections 37. Hinged to the outer ends of 35 the sections 37, are other sections 38 which are hinged at 39 to said sections 37 respectively and meet on the center longitudinal line of the car. Thus when the partition is collapsed, a crescent-shaped seat is provided which extends around the rear platform of the car and across the controller box 4 as shown in Fig. 2. In order to close the space between each section 37 and the adjacent seats 40 on either side, a small leaf 40 41 is hinged at 42 to each of the inner ends of the sections 37. When the partition is set up to form a reserved space for the motorman as shown in Fig. 1, sections 38 and 41 respectively are swung about their 45 hinges 39 and 42 until they lie flat upon the under section 37 on either side. In this position, the adjacent ends of sections 38 and 41 are brought together on a line indicated at 43 in Figs. 1 and 2. From an inspection of Figs. 1, 2 and 3, it will be seen 50 that the partition sections 5 terminate sufficiently high above the platforms 2 and 3 to permit the seat sections 37 to extend thereunder.

60 I claim:

1. In a car, spaced partition sections hinged to the inner wall of the car, said sections being thereby adapted to be folded against the inner wall of the car to be out of the way or to be moved into position

forming a compartment, and a tie-bar extending between the adjacent edges of said sections, said tie-bar constituting a barrier across the open space between said sections.

2. In a car, spaced partition sections 70 hinged to the inner wall of the car, said sections being thereby adapted to be folded against the inner wall of the car to be out of the way or to be moved into position forming a compartment, guides mounted on 75 the adjacent edges of said sections, and a flexible panel having means slidably engaging said guides.

3. In a car, the combination with the wall of said car, of spaced partition sections 80 hinged thereto, said sections being thereby adapted to lie against the car wall or caused to project therefrom at an angle, channeled guides mounted on the swinging edges of said sections, a roller extending 85 across the space between said sections when said sections project at an angle from said car wall, and a curtain carried by said roller and having means slidably engaging the channels in said guides. 90

4. In a car provided with a platform and a controller on said platform, a partition comprising sections spaced apart on opposite sides of said controller, and an intermediate section having its lateral edges slidably connected to the adjacent lateral edges of said spaced sections. 95

5. In a car, the combination with the wall of said car, of spaced partition sections hinged thereto, said sections being thereby 100 adapted to lie against the car wall or caused to project therefrom at an angle, channeled guides mounted on the swinging edges of said sections, a roller extending across the space between said sections when said sections project at an angle from said car wall, a curtain carried by said roller and having means slidably engaging the channels in said guides, and a tie bar pivotally mounted on one of said partition sections and releasably 105 engaging the other. 110

6. In a car provided with a platform and car controlling mechanism thereon, a collapsible barrier forming a reserved area around said controlling mechanism, said barrier comprising spaced sections hinged to the inner wall of said car and means extending across the space between said sections and holding said sections in position. 115

7. In a car provided with a platform and car controlling mechanism thereon, a collapsible barrier forming a reserved area around said controlling mechanism, said barrier comprising spaced sections hinged to the inner wall of said car and means extending across the space between said sections and holding said sections in position, said spaced sections being collapsible to lie against the inner wall of the car and said means for holding the sections in position 125 130

being mounted on one of said sections and adapted to releasably engage another.

sections, and a roller for said curtain jour- 45
naled in said bulkhead.

8. In a car, the combination with oppositely spaced partition sections suitably mounted to be moved into and out of partition-forming position, of a flexible curtain suitably rolled adjacent one end of said partition sections said curtain being provided with means adapting it to be attached to the adjacent lateral edges of said sections. 50

9. In a car, the combination with oppositely spaced partition sections suitably mounted to be moved into and out of partition-forming position, of a flexible curtain 55

suitably rolled adjacent one end of said partition sections said curtain being provided with means adapting it to be attached to the adjacent lateral edges of said sections, said attaching means adapting the lateral edges

20 of said curtain to slidably engage the lateral edges of said partition sections.

10. In a car, the combination of oppositely spaced partition sections suitably mounted to be moved into and out of partition-form-

25 ing position, means for positively locking said sections in partition-forming position,

and a flexible curtain having its lateral edges 30

slidably connected to the adjacent lateral edges of said spaced sections.

11. In a car, a partition comprising spaced

sections suitably mounted to swing into and

out of partition-forming position, a tie bar

having one end pivotally connected with

one of said sections and the other end there-

35 of adapted to releasably engage the other of

said sections and a flexible curtain having its

lateral edges slidably connected to said sec-

tions.

12. In a car, a partition comprising spaced

40 sections suitably mounted to swing into and

out of partition-forming position and a cur-

tain having its lateral edges slidably con-

nected to said sections, a curtain bulkhead

arranged adjacent the upper end of said sec-

45 tions, and a roller journaled in said bulkhead,

and a flexible panel carried by said roller and

slidably engaging said guides.

13. In a car, a partition comprising spaced

sections suitably mounted to swing into and

out of partition-forming position and a cur-

tain having its lateral edges slidably con-

nected to said sections, a curtain bulkhead

arranged adjacent the upper end of said sec-

50 tions, and a roller journaled in said bulkhead,

and a flexible panel carried by said roller and

slidably engaging said guides, said sections

55 being provided with a releasable tie bar for holding

said sections in partition-forming position.

14. In a car having a platform and a con-

troller on said platform, partition sections

spaced on opposite sides of said controller,

the adjacent edges of said sections being pro-

vided with guides, a tie bar having one end

connected to one section and the other end

thereof adapted to releasably engage the other

of said sections, a bulkhead mounted adjacent

the upper end of said sections, a roller journaled

60 in said bulkhead, and a flexible panel carried

by said roller and slidably engaging said guides.

15. In a car having a platform and a con-

troller on said platform, partition sections

spaced on opposite sides of said controller,

the adjacent edges of said sections being pro-

vided with guides, a tie bar having one end

connected to one section and the other end

thereof adapted to releasably engage the other

of said sections, a bulkhead mounted adjacent

the upper end of said sections, a roller journaled

65 in said bulkhead, and a flexible panel carried

by said roller and slidably engaging said guides,

the partition being terminated a sufficient dis-

70 tance above said platform to permit the disposa-

75 lation of seats therebeneath.

WILLIAM S. MENDEN.
